F. C. NICKOL

VALVE SPRING RETAINING DEVICE

Filed Feb. 2, 1925

Patented Sept. 22, 1925.

1,554,227

UNITED STATES PATENT OFFICE.

FREDERICK C. NICKOL, OF DAYTON, OHIO.

VALVE-SPRING-RETAINING DEVICE.

Application filed February 2, 1925. Serial No. 6,295.

To all whom it may concern:

Be it known that I, FREDERICK C. NICKOL, a citizen of the United States, residing at Dayton, in the county of Montgomery and 5 State of Ohio, have invented certain new and useful Improvements in Valve-Spring-Retaining Devices, of which the following is a specification, reference being had therein to the accompanying drawing.

10 This invention relates to valve spring retaining devices, such as are commonly employed in connection with internal combustion engines for the purpose of retaining the actuating springs for the valves on the valve stems and under compression.

15

The ordinary retaining device consists merely of a washer which forms a support for the lower end of the spring and is slipped over the valve stem and retained thereon by 20 a pin inserted through an opening in the stem, the washer usually having a recess in its lower surface to receive the pin and hold the same against displacement. To apply such a device to the valve stem it is necessary 25 that the valve should be held against vertical movement, the spring and washer placed upon the valve stem and the spring compressed and held under compression while the pin is inserted through the opening in 30 the valve stem. This is rather a difficult operation and usually requires considerable time for its completion.

One object of the invention is to provide a 35 valve spring retaining device of this character which can be quickly and easily applied to the valve stem or disconnected therefrom.

A further object of the invention is to provide such a device which will be held in positive engagement with the valve stem and which will not be disconnected therefrom by the operative movement of the valve stem or by any jar or vibration to which that stem may be subjected.

45 A further object of the invention is to provide such a device which will be very simple in its construction and which may be produced at a very low cost.

50 Other objects of the invention will appear as the device is described in detail.

In the accompanying drawings Fig. 1 is a vertical sectional view taken through the valve chamber of an internal combustion engine and showing my invention applied to the stem of the valve; Fig. 2 is an end ele-

vation of the retaining device showing the same applied to the valve stem; Fig. 3 is a bottom plan view of the same; Fig. 4 is a section taken on the line 4—4 of Fig. 1; Fig. 5 is a side elevation of the retaining device 60 showing the same applied to the valve stem; Fig. 6 is a section taken on the line 6—6 of Fig. 1; and Fig. 7 is an end view of the retaining device showing the parts separated to disconnect the same from the valve stem. 65

In these drawings I have illustrated one embodiment of my invention and have shown the same as applied to a valve of a well known type but it will be understood that the invention may take various forms and 70 may be applied to valves of various kinds.

In that embodiment of the invention here illustrated I have shown the same as applied to the valve stem 1 of an ordinary type valve 2, which is slidably mounted in 75 a vertical bearing or guideway 3 carried by the cylinder block 4. The stem 1 of the valve extends for a considerable distance below its bearing and a coil spring 5 encircles this stem and is confined between the 80 lower part of the bearing, or that part of the engine in which the bearing is formed, and the retaining device which is secured to the lower portion of the stem. The retaining device as here shown comprises a disk or 85 washer which forms a support for the spring and is divided diametrically into two similar parts, these parts being in the present instance, substantially semi-circular in shape, as shown at 6 in Fig. 3. The retaining device as a whole is preferably formed from sheet metal and I prefer to construct 90 the same by forming the disk and its associated parts from a blank of sheet metal and then dividing the same diametrically 95 into two parts. The body or transverse portion of the disk or washer, which constitutes a support for the spring, is preferably recessed in its lower side, by pressing the central portion of the same upward, so as to 100 give the same substantially a concavo-convex shape. The adjacent edges of the semi-circular members 6 are provided with recesses opposed one to the other and adapted to receive the valve stem. Each member 6 is 105 provided adjacent to the recess, with a part adapted to be moved into and out of engagement with a stop on the valve stem. In the present device, this stop is in the form of a shoulder 7 which is formed on the stem by 110

providing the latter with a circumferential flange 8 near the lower end thereof. In the device here shown, the metal which is displaced to form the recesses in the edges of 5 the two members 6 is pressed downwardly and drawn out to form depending flanges 9, which are of such a width that they will enter the groove 8 in the valve stem so that the lower edges thereof may engage the stop 10 7 on the valve stem. The transverse portion of each member of the washer slopes downwardly and outwardly toward the peripheral edge thereof, and this edge is turned upwardly, as shown at 10, to form a seat for 15 the valve spring 5. The two parts of the washer are connected one to the other and are capable of relative movement to permit the same to be moved into and out of engagement with the stop on the valve stem 20 and the arrangement is such that the pressure of the spring 5 on the two parts of the washer will force the same into firm engagement with the stop on the stem and retain the same in that position until they 25 are positively actuated to disconnect the washer from the stem and permit the removal of the spring. Preferably the two parts of the washer are pivotally connected one to the other at points some distance 30 above the level of the washer. To this end each member of the washer is provided at its opposite ends with an upwardly extending lug or ear 11 which is preferably formed integral with the member itself. The corresponding ears on the two members, that is, the ears carried by the adjacent ends of the two members, are opposed one to the other and have parts which contact one with the other and constitute a fulcrum about which 35 40 45 50 55 60 65 70 75 80 85 90 95 100 105 110 115 120 125 130 135

facilitate the disconnection of the retaining device from the stem the lower portions of the ears 11, below the fulcrum point, are cut away to provide a recess or space 15 adapted to receive the bit of a screw driver, or other suitable implement, which may be inserted between the lower portions of the ears and manipulated to spread the same apart and move the parts 9 thereof out of engagement with the shoulder on the stem, this movement being permitted by the pivotal connections between the corresponding ears. This connection while serving to permanently connect the two parts of the device one to the other and to hold the same against substantially axial displacement with relation one to the other will nevertheless permit of the free pivotal movement thereof.

As will be apparent from the foregoing description the retaining device is very simple in its construction, comprises but few parts and is of such a character that it can be produced at a very low cost by stamping the same from sheet metal. To install the device on the valve stem it is only necessary to seat the valve on the washer within the space between the ears 11 and then place the spring and retaining device about the valve stem, hold the valve against upward movement with one hand and exert upward pressure on the retaining device with the other hand, thus compressing the spring and forcing the retaining device lengthwise of the stem. The action of the spring on the two parts of the retaining device will tend to force the stop engaging parts 9 thereof inwardly and as soon as these parts have cleared the shoulder 7 they will spring into engagement therewith and, when the upward pressure thereon has been relieved, will remain in engagement with the shoulder 7 and support the spring on the valve stem under compression. The construction of the device is such that the action of the spring thereon will firmly hold the same in operative engagement with the stem at all times and will not permit the same to be disconnected from the stem by vibration or jars imparted thereto. To disconnect the retaining device from the stem and permit the removal of the spring it is only necessary to insert the bit of a screw driver in the recess 15 at one end of the device and twist the same, thereby imparting pivotal movement to the two members and moving the parts 9 out of engagement with the shoulder and thus permitting the spring to move the retaining device downwardly past the stop on the stem.

While I have shown and described one embodiment of my invention I wish it to be understood that I do not desire to be limited to the details thereof as various modification may occur to a person skilled in the art.

Having now fully described my invention, what I claim as new and desire to secure by Letters Patent, is:

1. A device for retaining a spring on a valve stem, comprising two members shaped to receive the valve stem between them and to form a seat for the spring, and having parts movable into and out of engagement with a stop on said valve stem, and each having lugs extending from the opposite edges thereof lengthwise of said spring, and means for pivotally connecting the adjacent lugs of the two members one to the other at points spaced from the seat for said spring. 70
2. A device for retaining a spring on a valve stem, comprising two members shaped to receive the valve stem between them and to form a seat for the spring, and having parts movable into and out of engagement with a stop on said valve stem, and each having lugs extending from the opposite edges thereof lengthwise of said spring, and connecting members pivotally connected with the adjacent lugs at the respective ends of said members to pivotally connect said members one to the other. 80
3. A device for retaining a spring on a valve stem, comprising two members shaped to receive the valve stem between them and to form a seat for the spring, and having parts movable into and out of engagement with a stop on said valve stem, and each having lugs extending from the opposite ends thereof lengthwise of said spring, the corresponding lugs at the respective ends of said members having abutting parts to form fulcrums about which said members may move, and connecting devices to hold said corresponding lugs against bodily displacement relative one to the other but to permit of their pivotal movement about said fulcrums. 90
4. A device for retaining a spring on a valve stem, comprising two members shaped to receive the valve stem between them and to form a seat for the spring, and having parts movable into and out of engagement with a stop on said valve stem, and each having lugs extending from the opposite ends thereof lengthwise of said spring, the corresponding lugs at the respective ends of said members having cooperating parts to form fulcrums about which said members may move, and connecting members for said corresponding members, each loosely connected at its ends with the respective lugs. 100
5. A device for retaining a spring on a valve stem, comprising two members shaped to receive the valve stem between them and to form a seat for the spring, and having parts movable into and out of engagement with a stop on said valve stem, and each having lugs extending from the opposite ends thereof lengthwise of said spring, the
- corresponding lugs at the respective ends of said members having cooperating parts to form fulcrums about which said members may move, and connecting parts for connecting the adjacent lugs of the two members to pivotally connect said members one to the other. 110
6. A device for retaining a spring on a valve stem, comprising two members shaped to receive the valve stem between them and to form a seat for the spring, and having parts movable into and out of engagement with a stop on said valve stem, and each having lugs extending from the opposite ends thereof lengthwise of said spring, and connecting members pivotally connected with the adjacent lugs at the respective ends of said members to pivotally connect said members one to the other, said adjacent lugs having those parts thereof, which are adjacent to the seat for said spring spaced apart to receive an implement for moving the same relatively one to the other. 120
7. A device for retaining a spring on a valve stem, comprising two substantially semi-circular members arranged edge to edge to form a support for the spring and having opposed recesses in their adjacent edges to receive a valve stem, each of said members having a downwardly extending part at the edge of said opening to engage a stop on said valve stem, and each of said members having at its opposite ends lugs extending lengthwise of said spring, and means for pivotally connecting the lugs at the adjacent ends of the two members one to the other. 130
8. A device for retaining a spring on a valve stem, comprising a concavo-convex spring supporting washer divided diametrically into two parts, said parts having opposed recesses in their adjacent edges to receive a valve stem and having downturned flanges surrounding said recesses and arranged to engage a stop on the valve stem, and also having their outer edges turned upwardly to form a seat for the spring, each part of said washer having lugs extending upwardly from the opposite ends thereof, and means for pivotally connecting the lugs at the adjacent ends of the two parts one to the other. 140
9. A device for retaining a spring on a valve stem, comprising two substantially semi-circular members, each formed from a single sheet of metal, having a recess in its inner edge to embrace the valve stem and having a downturned flange extending about said recess to engage a stop on said valve stem, each of said members sloping downwardly toward the peripheral edge thereof and having said peripheral edge turned upwardly to form a seat for a spring, each of

said members also having ears extending upwardly from the opposite ends thereof, and means for pivotally connecting the adjacent ears of the two members one to the other.

10. A device for retaining a spring on a valve stem, comprising two substantially semi-circular members each formed from a single sheet of metal, having a recess in its 10 inner edge to embrace the valve stem and having a downturned flange extending about said recess to engage a stop on said valve stem, each of said members sloping downwardly toward the peripheral edge thereof

and having said peripheral edge turned upwardly to form a seat for a spring, each of said members also having ears extending upwardly from the opposite ends thereof, and means for pivotally connecting the adjacent ears of the two members one to the other, 15 said adjacent ears having parts thereof spaced one from the other to receive an implement by means of which said members may be moved with relation one to the other to disconnect the same from said valve stem. 20 25

In testimony whereof, I affix my signature hereto.

FREDERICK C. NICKOL.
